UNITED STATES PATENT OFFICE.

JOHN JANES, OF CAMBRIDGEPORT, MASSACHUSETTS, ASSIGNOR OF ONE-HALF TO GEORGE WOODS, OF SAME PLACE.

REED-ORGAN.

SPECIFICATION forming part of Letters Patent No. 253,291, dated February 7, 1882.

Application filed October 27, 1881. (No model.)

To all whom it may concern:

Be it known that I, JOHN JANES, a citizen of the United States, residing at Cambridgeport, in the county of Middlesex and State of Massachusetts, have invented certain new and useful Improvements in Reed-Organs; and I do hereby declare that the same are fully described in the following specification and illustrated in the accompanying drawings.

10 This invention relates to improvements in reed-organs; and it consists in the combination, with an ordinary unison set of reeds, of an improved celeste attachment, which is carried out as follows, reference being had to the accompanying drawings, on which—

Figure 1 represents a plan view of the invention. Fig. 2 represents a longitudinal section; and Fig. 3 represents a cross-section on the line A B, shown in Fig. 1.

20 Similar letters refer to similar parts wherever they occur on the different parts of the drawings.

a is the wind-chamber of an ordinary reed-organ, on which b is the reed-board, provided 25 with tube-boards c c', an octave set of reeds, d d', and a unison set of reeds, d' d', as usual.

D is a stop for the reeds d d', and D' is a similar stop for the reeds d' d', in the ordinary manner, which stops are operated by means of 30 stop-handles and suitable connecting mechanism therefrom, as usual, such handles and connecting mechanism being, however, not shown in the drawings.

e e are the valves for the reeds d d'.

35 f and f' are the swell-tops, with perforated pitman-bar g and push-pins h h, as usual.

i is the key-frame, and k k represent the ordinary keys for actuating the valves e e.

l is the wind-chamber for the celeste reeds 40 m m, which wind-chamber is connected to the main wind-chamber a by means of the passage n, as shown in Fig. 2.

45 o o are the valves for the celeste reeds m m, which valves are actuated from the keys k k by means of the usual adjustable screws, p p, knee-levers q q, and push-pins r r, as shown in the drawings.

S is the tube-board for the celeste reeds m

m. The tube-board S is provided with upper openings, t t, covered by the stop T, and also 50 with side openings or perforations, u u, covered by the stop U, which stops are actuated by means of suitable handles and connecting mechanism from such handles to said stops, in the usual manner, such connecting mechanism 55 and handles being, however, not shown in the drawings.

The reeds d' d' and celeste reeds m m are tuned together to the same pitch when the stops D', T, and U are all open, as shown in 60 dotted lines in Fig. 2, and consequently when either of the stops T or U is opened, as well as the valves o o, the reeds m m will sound out of tune, and therefore a vox celeste is produced by playing the unison set of reeds d' d', together with the reeds m m, and opening the stop D' and either of the stops T or U; and it will thus be seen that the reeds m m may be played in connection with the unison set of reeds d' d' in harmony by opening all the stops 70 D', T, and U, and as a vox celeste accompaniment by opening the stop D' and one of the stops T or U only; also, if so desired, the set of reeds m m may be played alone by opening both their stops T and U. By this my improved vox celeste arrangement it is only necessary to open one stop on the tube-board S to produce a vox celeste in combination with the opening of the stop D' on the unison set of reeds d' d', as described. 75 80

What I wish to secure by Letters Patent, and claim, is—

In a reed-organ, the combination, with a unison set of reeds, d' d', and its stop D', of an additional set of reeds, m m, and tube-board S, 85 with its two stops T U and corresponding reed-openings, the reeds m m being so tuned as to be in tune when both of its stops T U are open, and out of tune when either of said stops alone is open, as and for the purposes described. 90

In testimony whereof I have affixed my signature in presence of two witnesses.

JOHN JANES.

Witnesses:

ALBAN ANDRÉN,
FRANCIS ALLEN.
